United States Patent Office

Des. 211,452
Patented June 18, 1968

211,452

SLIDING WINDOW LATCH

Unto E. Petrell, Brooklyn, N.Y., assignor to Allen Stevens Corporation, Woodside, N.Y., a corporation of New York

Filed June 8, 1967, Ser. No. 7,406

Term of patent 14 years

(Cl. D10—10)

Fig. 1.

Fig. 2.

Fig. 3.

Fig. 4.

Fig. 5.

FIG. 1 is a perspective view of my sliding window latch in the open position;

FIG. 2 is a side elevational view of the latch in the closed position;

FIG. 3 is a front view thereof;

FIG. 4 is a side elevational view of the latch from the handle side; and

FIG. 5 is an end view of the sliding window latch.

The dominant features of my design reside in the portions shown in full.

I claim:

The ornamental design for a sliding window latch, as shown and described.
